UNITED STATES PATENT OFFICE.

ALBERT FRIEDELEY, OF CHICAGO, ILLINOIS, ASSIGNOR OF ONE-HALF TO
HERMAN F. VOSHARDT, OF CHICAGO, ILLINOIS.

METAL ROOFING TILE OR SHINGLE.

SPECIFICATION forming part of Letters Patent No. 740,842, dated October 6, 1903.

Application filed April 27, 1903. Serial No. 154,407. (No model.)

To all whom it may concern:

Be it known that I, ALBERT FRIEDELEY, a citizen of the United States, residing at No. 487 West Congress street, in the city of Chicago, in the county of Cook and State of Illinois, have invented new and useful Improvements in Metal Roofing Tiles or Shingles, of which the following is a specification, reference being had to the accompanying drawings, forming a part thereof.

The purpose of this invention is to provide an improved form of metal roofing tile or shingle adapted to interlock and afford practically water-tight junctions without soldering.

15 It consists in the features of construction set out in the claims.

In the drawings, Figure 1 is a plan view showing three of my improved tile-sections interlocked as in the practical construction 20 of a roof therewith. Fig. 2 is a section at the line 22 on Fig. 1. Fig. 3 is a section at the line 33 on Fig. 1. Fig. 4 is a section at the line 44 on Fig. 1. Fig. 5 is a detail similar to Fig. 2, showing the seam closed. Fig. 6 is a detail 25 similar to Fig. 3, showing the seam closed.

I have illustrated my invention as applied to metal roofing tiles or plates which are in form oblong equilateral hexagons and are designed to be arranged on the roof with their 30 longest diagonal and the two opposite parallel sides extending up and down on the roof—i. e., in the direction of maximum slope—which direction is for convenience of reference hereinafter termed “longitudinal,” such 35 tiles being placed in transverse rows with their said opposite parallel edges abutting and joined, whereby there are formed between each two consecutive tiles in each row reentrant angles equal to the minimum angles of the plates, respectively, and adapted 40 thereby to receive such angles of the tiles of the next row above and below. In the drawings each of these hexagonal plates 1 has the opposite parallel longitudinal edges formed 45 so that one of said edges of each plate is adapted to interlock with the other of said edges of the adjacent plate to form an upstanding rib-seam. For this purpose at one 50 of said edges the metal is folded upward and refolded down inward—i. e., on the side toward the body of the plate—forming a down-

wardly-open element 2, and the other of said edges is folded upward and refolded down outwardly and back again upwardly between said first two folds, forming the element 3 of 55 such rib-seam. These two elements are adapted to be united by longitudinal sliding of the former within the latter, so that they are interlocked, as seen in Fig. 2, and the two plates thus united are inseparable except 60 by the same longitudinal movement by which they were engaged. The two upper edges of each plate are folded back upwardly, forming flanges 44, and the two lower edges are folded back inwardly, forming flanges 55. The 65 flanges 44 do not extend to the geometrical angles or corners of the hexagonal outline of the plate; but at the upper apex of each plate between the two flanges 44 the plate is extended to form a lug 6, and at the lower end 70 of each flange the metal of the plate is left unfolded for a short distance, forming, after the flanges 44 are turned, lugs 99. The metal of the plate is embossed or struck up in the line of the longest diagonal at the lower 75 apex between the flanges 55 of the lower sides, forming a hollow upstanding boss or rib 10 of sufficient height to stride or saddle upon the upper end of the rib-seam formed by the interlocking of the elements 2 and 3. 80 Either or both of the pairs of flanges at the upper and lower sides—to wit, flanges 44 and 55—are left projecting somewhat obliquely in the original formation of said flanges, and after the mounting of one transverse row of 85 plates on the roof the next row above is engaged by lodging the hollow boss or saddle 10 of another plate over the rib-seam 23 and moving the plate thus lodged upward to engage its flanges 55 under the flanges 44 of 90 two adjacent plates of the first row. This interlocking, it will be seen, can be performed at the finish of the longitudinal movement, by which the seam elements 23 of each two adjacent plates of the second row are interlocked, as described. The plates may be secured to the roof by nails through the lugs 6 and 7, and these nails will be covered in the case of each plate by the application of the 95 next succeeding plate above. The rib-seams 100 formed by the interlocking of the elements 2 and 3 will be closed together by proper appli-

ances for clenching such seams, either as the 5
seams are formed successively or as a row of
plates is completed, this being preferably done
before the application of the next row above,
so that the seam may be closed up to the end
under the saddle 10, as well as at the uncov-
ered portion below such saddle. The lapped
seams made by the engagement of the flanges
5 under the flanges 4 will also be securely
10 closed by hammering as each plate or row of
plates is put in place and secured by the nails
through the lugs at the upper side. By this
means it will be seen that each plate is adapt-
ed to shed the water onto the next plate be-
15 low at a distance beyond any lap or seam
through which it might pass and that each
plate so protects the plates which it overlaps
at the lower edge that in case of rain driven
by the wind upward or against the slope of
20 the roof it cannot pass these seams without
being obliged to follow a very circuitous path
around through the folds or interlappings of
the plates, which are joined at said seams.
The structure is thereby adapted to make a
25 water-tight roof without soldering.

I claim—

1. A roof comprising hexagonal tiles which
are joined successively in transverse rows by
doubly interlocking upstanding rib-seams at
30 their longitudinal edges, and by interlapping
flat seams at their oblique upper and lower
edges.

2. A metal-tile roof comprising hexagonal
metal tiles having their opposite parallel lon-
35 gitudinal edges formed respectively with an
upturned flange refolded inwardly upon itself
and overhanging the plate, and an upstand-
ing flange refolded outwardly downward and
inwardly upward, the former adapted to be

interlocked with the latter by endwise sliding 40
engagement to form longitudinal upstanding
rib-seams, the upper and lower oblique edges
of said tiles being provided with flanges which
are reflexed outward and inward respectively,
whereby they are adapted to be engaged by 45
broadside movement of the one toward the
other in the endwise interlocking movement
of the longitudinal edges.

3. In a metal-tile roof, hexagonal metal tiles
having upstanding reflexed flanges at their 50
opposite lateral edges, adapted to interlock
endwise to form longitudinal upstanding rib-
seams between the adjacent tile of each
transverse row, and having at their upper and
lower oblique edges flanges reflexed out- 55
wardly and inwardly respectively, and hav-
ing terminating at the lower apex the longi-
tudinal upstanding hollow boss or saddle, 10,
adapted to stride the upstanding rib-seam of
the next lower row. 60

4. In a metal-tile roof, hexagonal metal tiles
having their adjacent edges correspondingly
flanged for interlocking with the tiles of each
row overlapping at their lower edges the ad-
jacent tiles of the next lower row, and hav- 65
ing at their upper edges lugs projecting up-
wardly beyond the fold-lines of the interlock-
ing flanges to afford means for securing each
tile to the roof underneath the next overlap-
ping tile. 70

In testimony whereof I have hereunto set
my hand, in the presence of two witnesses, at
Chicago, Illinois, this 22d day of April, A. D.
1903.

ALBERT FRIEDELEY.
In presence of—
CHAS. S. BURTON,
FREDK. G. FISCHER.
